Primary Examiner — Cathy Anne MacCormac(74) *Attorney, Agent, or Firm* — Global IP Counselors, LLP**CLAIM**

The ornamental design for a pet toy, as shown and described.

DESCRIPTION

FIG. 1 is a front perspective view of a pet toy in accordance with our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines depict environmental subject matter, are for illustration only, and form no part of the claimed design.
